UNITED STATES PATENT OFFICE.

ISAAC N. ELLIOTT, JOHN WM. COLLINS, AND PETTIS A. REID, OF RICHMOND,
INDIANA.

FENCE-LINK.

SPECIFICATION forming part of Letters Patent No. 430,177, dated June 17, 1890.

Application filed June 27, 1889. Serial No. 315,825. (No model.)

To all whom it may concern:

Be it known that we, ISAAC N. ELLIOTT,
JOHN WM. COLLINS, and PETTIS A. REID, citizens
of the United States of America, residing
5 at Richmond, in the county of Wayne and
State of Indiana, have invented certain new
and useful Improvements in Fence-Links, of
which the following is a specification, reference
being had therein to the accompanying
10 drawings.

Our invention is a new article of manufacture,
which we have named a Fence-Link, its
use being to connect sections of what is
usually known as "combination wire and slat
15 fencing" at the cables of the same quickly,
cheaply, and effectually, and as an article of
manufacture is wholly distinct from that of
fencing, as much so as that of nails and staples.
Heretofore the connection of two sec-
20 tions of this style of fencing has been accom-
plished by various methods, always using the
contiguous extremities of the sections as the
connecting material—such as removing a slat
from each extremity of the sections to be
25 joined, discarding one slat, and after arrang-
ing the cables properly inserting the remain-
ing slat in the spaces formerly occupied by
the two; also, by the cables being tied to-
gether in various styles and by nailing the
30 fencing to the post nearest the end, cutting
away the overplus, and then nailing the end
of the next roll of fencing to the same post,
and so on, all of which we have found to be
either tedious or wasteful.

35 In the drawings, Figure 1 gives a ground
plan of a section of fencing, showing the
points of cutting a section of fencing and the
relative position of the parts. Fig. 2 is a per-
spective view showing the method of con-
40 necting two sections of fencing, with the link
in position. Fig. 3 represents a completed
connection.

The link F is of a tenacious metal, having
a longitudinal shaft g, terminating in hooks
45 ff, the said hooks preferably, though not neces-
sarily, turned toward each other, resting at an
angle of ninety degrees (90°) or less to the
plane of the shaft g.

As the combination wire and slat fencing
50 is so well known, it is scarcely necessary to

enter into the details of its construction fur-
ther than to state that it is composed of ver-
tical slats, either metal or wood, bound at in-
tervals by horizontal wires in pairs, usually
termed "cables," the said cables embracing 55
the slats and more or less twisted between
the slats. In manufacturing this fencing to
transport, it is the general custom to make it
into rolls, and then when it is to be attached
to posts for service these rolls must be con- 60
nected. The practice in dividing this style
of fencing or in discharging the completed
rolls from the machines is usually to cut the
wires embracing the slats at either of the
points a' a² a⁴ and b² b⁴ b⁵, Fig. 1, thus re- 65
moving the slat E, which in a factory may be
reused in other fencing, occasioning no waste
of slats. It will be observed that if the wires
be cut at a⁴ b² there will be left to each of
the adjacent sections a long and short part 70
a³ b' and b³ a⁵. It will also be seen in Fig. 1
that in front and rear, respectively, of the
slats C D at each cable or pair of wires are
spaces A B, formed by the wires a b, twisted
wires ba, and slat C, and the wires a b, 75
twisted wires ab and slat D, respectively,
which we make use of for the insertion of the
hooks ff of the link F, thus joining the two
sections of fencing together, as shown in Fig.
2. It will be observed that we depend upon 80
the resistance of the twisted wires or cables
ba and ab for the efficacy of the link F; but
as a precautionary means we turn back the
short arms a⁵ b', forming hooks, Fig. 2, and
also wrap the adjacent twists ab ba and link 85
F with extensions a³ b³ to the extent of their
length, Fig. 3. By so doing we also prevent
the link F being easily or accidentally disen-
gaged.

In using very heavy wires a b with numer- 90
ous twists at ab ba it is unnecessary to use
the extensions a³ b³, so they may be cut away,
leaving all the parts as are a⁵ b' in either Fig.
1 or 2, which renders the sections easily sepa-
rated for portable purposes and reunited. 95

Having thus described our invention, we
claim—

1. The combination, with the horizontal
cables of fencing, of a metallic link composed
of a horizontal body terminating in hooks, 100

preferably turned toward each other, the said hooks engaging the adjacent cables within openings formed between the members of each cable near its extremity, as specified, 5 and for the purpose set forth.

2. The combination of the link F, engaging the wires $a\ b$ within the spaces A B, with the slats C D, the wires $a\ b$, embracing the said slats C D, the twisted wires or cables $ba\ ab$, 10 the short extensions $a^5\ b'$, turned back upon the twisted cables ba and ab , respectively, forming hooks, and the long extensions $a^3\ b^3$,

embracing or partially embracing the combined link F and twisted cables ba and ab , as shown, and for the purpose set forth. 15

In testimony whereof we affix our signatures in presence of two witnesses.

ISAAC N. ELLIOTT.
JOHN WM. COLLINS.
PETTIS A. REID.
